UNITED STATES PATENT OFFICE.

CHARLES T. MEYER AND VICTOR E. MEYER, OF JERSEY CITY, NEW JERSEY,
ASSIGNORS TO LINCOLN D. FARR, OF PHILADELPHIA, PA.

DESIGN FOR OIL-CLOTH PATTERN.

Specification forming part of Design No. **11,391**, dated September 2, 1879; application filed August 7, 1879.
[Term of patent 3½ years.]

To all whom it may concern:

Be it known that we, CHARLES T. MEYER and VICTOR E. MEYER, of Jersey City, New Jersey, have produced or invented a new and original Design for an Oil-Cloth Pattern, of which the following is a specification.

Our design for an oil-cloth pattern is fully shown in the accompanying photographic illustration.

The design comprises a series of square figures, A, B, D, and E. Each figure A is ornamented with stems, leaves, and flowers *a*, and is cut off at one corner by the triangular figure *b*. Diagonally-opposite corners of each figure B are occupied by square figures *d*, which meet in the center of the figure B, and are each ornamented with a central rosette, *e*. Each figure D has a border, *f*, on each of its

four sides, and has in the center an ornament, *g*, of a character too fully shown to need description. Each figure E has a plain ground-work, on which is arranged a foliated design, *m*, comprising stems, leaves, and flowers.

Irrespective of the colors employed, we claim—

The design for an oil-cloth pattern, substantially as described, and as shown in and by the accompanying drawing.

In testimony whereof we have signed our names to this specification in the presence of two subscribing witnesses.

CHAS. T. MEYER.
VICTOR E. MEYER.
